SYSTEM FOR THE CONTROL OF DIRIGIBLE DEVICES FROM A DISTANCE.

1,374,124.

Specification of Letters Patent.

Patented Apr. 5, 1921.

Application filed June 3, 1918, Serial No. 237,921. Renewed June 24, 1920. Serial No. 391,552.

To all whom it may concern:

Be it known that I, ALBERT D. TRENO, a citizen of the United States, and a resident of New York, in the county of New York and State of New York, have invented certain new and useful Improvements in Systems for the Control of Dirigible Devices From a Distance, of which the following is a specification.

10 Some of the objects of this invention are to provide an improved system for the control of dirigible bodies from a distance whereby a plurality of different mechanisms may be selectively controlled by a minimum 15 number of impulses or signals received from a distance; to provide a common control for distributing motive fluid to a plurality of different actuating devices and providing selective means operated from a distance to 20 position said common control in a predetermined manner to cause the operation of any one of said actuating devices; to provide other improvements as will appear herein-after.

25 In the accompanying drawings, Figure 1 is a diagrammatic plan partly in section of a system embodying one form of this invention; Fig. 2 is a detail in elevation of one part of the control mechanism; Figs. 3 30 to 10 inclusive represent longitudinal sections of a control part of the system showing the same in various positions; Fig. 11 is an enlarged longitudinal section of a detail forming a part of this invention; Fig. 12 35 is a detail in plan of the centering device controlled by the gyroscope; and Fig. 13 is a detail in bottom plan of the commutator construction.

40 Referring to the drawings, one embodiment of this invention comprises any suitable dirigible device, for example a marine vessel (not shown), which is provided with a rudder 10 pivotally connected thereto to swing with respect thereto about a fixed 45 axis 11. To oscillate the rudder 10 about its axis 11 under pneumatic pressure, a cylinder 12 is rigidly secured to the vessel and is provided with a piston 13 arranged to reciprocate therein and which is rigidly secured to one end of a piston rod 14, the other end of which has a pivoted connection 15 with a link 16 which in turn is pivoted at 17 to the arm 20 which is rigid with the

rudder 10. The piston 13 is normally yieldingly held in a central position in its cylinder 12 by means of two spiral springs 21 and 22 arranged within the cylinder 12 upon ends of the piston 13 and consequently the rudder also is normally yieldingly held in a central position. For supplying compressed 55 air to the cylinder 12 and to other devices mounted upon the vessel to perform various functions, as will appear hereinafter, a tank 23 or other suitable source of air or other fluid under pressure is mounted upon the 60 vessel and is connected to the various devices as will be described hereinafter.

For controlling the distribution of fluid under pressure from the source 23 to various fluid actuated devices on the vessel, a main 70 distributing valve is provided comprising a tubular casing 24 having a cylindrical bore in which a cylindrical plug 25 is snugly but rotatably fitted. The valve casing 24 is provided on one side with two fluid inlet 75 ports 26 and 27, an exhaust port 28, and three additional ports 30, 31 and 32, and upon its opposite side with two exhaust ports 33 and 34 and four other ports 35, 36, 37 and 38. The valve casing 24 is also provided with two oppositely arranged ports 40 and 41 preferably extending in a direction substantially perpendicular to the ports 30, 35 of the casing and opening inwardly against the periphery of the plug 25. The 80 valve plug 25 is provided with four annular recesses 42, 43, 44 and 45, the first 42 communicating with the exhaust port 33; the second 43 with the inlet port 26; the third 44 with the inlet port 27; and the fourth 45 85 with the exhaust port 28. One end of the valve plug 25 is provided with a circumferential series of eight longitudinally arranged passages 50, 51, 52, 53, 54, 55, 56, 57, one of which as 57 is normally in communication 90 with the annular recess 43 and the remaining passages 50 to 56 inclusive being normally in communication with the annular recess 42 while all of said ports are adapted to register respectively with the ports 30, 35, 40 and 41, and with respect to each other are spaced circumferentially forty-five degrees apart. The opposite end of the valve plug 25 is provided with a group of eight circumferentially arranged longitudinally 100 disposed passages 60, 61, 62, 63, 64, 65, 66

and 67, two of which, as 66 and 67, are normally in communication with the annular recess 44 and the remaining passages 60 to 65 normally in communication with the annular recess 45, all of said passages being adapted to register respectively with the port 38, and are furthermore spaced circumferentially forty-five degrees apart with respect to each other.

10 The intermediate body part of the plug 25 is provided with a series of passage comprising seven circumferentially arranged longitudinal passages 70, 71, 72, 73, 74, 75 and 76 and one passage 77 bored into the 15 plug 25 and having two openings 78 and 79 on the surface of the plug, the latter being in communication with a passage 79' extending diametrically through the plug 25. The opening 78 is adapted to register 20 successively with the ports 32 and 37 and the opening 79 is adapted in one position to register directly with the exhaust port 34 and in a second position to register indirectly with the exhaust port 34 by way of 25 the passage 79'. The passage 76 is normally in communication with the annular recess 44 and is arranged to register with either the port 32 or the port 37 according to the position of the valve plug 25, while 30 the passages 70 to 75 inclusive are respectively adapted to register with either the pair of ports 31 and 32 or the pair of ports 36 and 37 according to the position of the valve plug 25. The passages 70 to 77 inclusive are angularly spaced one with respect to another at a forty-five degree angle and consequently each eighth of a revolution of the valve plug 25 brings a different passage into operation.

35 40 From the foregoing it will be evident that the plug 25 is provided with three sets of control passages, and in this connection it should be noted that the respective passages of each set are in longitudinal alinement 45 with the respective passages of the two other sets so that any movement of the plug through one eighth of a revolution will bring three different passages into a position for control purposes.

50 For automatically controlling the flow of pressure fluid from the tank or source 23 through the valve casing 24 to maintain the vessel automatically upon a predetermined course, as will appear hereinafter, an auxiliary valve 80 is arranged to reciprocate in a fixed auxiliary casing 81 and the opposite ends of the valve 80 are extended to form cores 82 and 83 which reciprocate in fixed solenoids 84 and 85 respectively. The 55 valve 80 is normally held central by the springs 86 and 87. The valve casing 81 is provided with an inlet pipe 90 which connects the valve casing with the source 23 of compressed air, and the casing 81 is also 60 connected by two oppositely disposed pipes 65

91 and 92 with the oppositely disposed ports 31 and 36 of the main valve casing 24. The valve 80 is formed with an annular recess 93 with which the supply pipe 90 normally communicates and the parts are so arranged 70 that when the valve is in a central position, as shown in Fig. 1, no air will be allowed to flow from the inlet pipe 90, through the valve casing 81 to either of the pipes 91 or 92, and these latter will be permitted to exhaust through the open ends of the valve casing 81. When, for example, the left hand solenoid 84 is energized the auxiliary valve 80 will be drawn to the left a sufficient distance to establish communication 80 between the inlet pipe 90 and the pipe 91 while leaving the pipe 92 open to the exhaust, but when the current is broken through the solenoid 84 and the right hand solenoid 85 is energized, the auxiliary valve 85 80 will be drawn to the right to establish communication between the inlet pipe 90 and the pipe 92 and to leave the pipe 91 open to the exhaust.

When the steering of the vessel is under 90 the automatic control of valve 80 the main valve plug 25 is in such a position as to establish communication between the pipe 91 and a pipe 94 by way of one of the passages, as 70, and to also establish communication between the pipe 92 and a pipe 95 by way of another of the passages, as 73, see Fig. 3.

The pipe 94 is connected to the steering control cylinder 12 to communicate with 100 one end thereof and the pipe 95 is connected to the cylinder 12 to communicate with the opposite end, the arrangement being such that the piston 13 is intermediate the inlets of the two pipes and is accordingly 105 moved as one or the other supplies pressure fluid.

For automatically energizing the solenoids 84 and 85 to maintain the vessel upon a predetermined course, any suitable direction maintaining means may be provided but in the form of the invention shown there is provided for this purpose in a suitable casing 96 a gyroscope which is provided with a stem 97 arranged to rotate 115 with respect to the vessel in a suitable bearing 98 fixed with respect to the vessel, the stem 97 being held by the gyroscope against rotation in space with respect to its longitudinal axis. In longitudinal alinement 120 with the stem 97 is a spindle 99 which is arranged to rotate in a fixed bearing 100 and has its lower portion in the form of a hollow cylinder 101 having a cap 102 fixed over its lower end, and within this cylinder 101 125 is arranged to reciprocate a piston 103 which is fixed upon the end of a piston rod 104, the lower portion of which projects slidably through the cap 102 and through a yoke 105 fixed upon the upper end of the 130

stem 97. The lower end of the piston rod 104 has fixed thereon a clamping disk 106 arranged to coöperate with the yoke 105 to clamp the yoke against the cap 102 to hold 5 the spindle 99 fixed with respect to the gyroscope stem 97. A compressed spiral spring 107 normally presses the piston 103 upwardly to clamp the yoke 105 to the cap 102. For forcing the piston 103 down- 10 wardly to disconnect the spindle 99 from the stem 97 the upper portion of the cylinder 101 communicates through a longitudinal passage 108 with an annular recess 109 in the spindle 99 and from the recess 109 by 15 way of a pipe 110 to the port 38 of the main valve casing 24. The spindle 99 has fixed thereto to move therewith a segmental contact disk 111 having two points of insulation 112 to form two contact segments 113 20 and 114, the first 113 being connected by a conductor 115 through a slip ring 113' with the winding of the solenoid 84, and the second 114 being connected by a conductor 116 through a slip ring 114' with the winding 25 of the solenoid 85. A contact arm 117 is secured to a fixed part such as a bracket 118 and normally rests upon one point of insulation 112 between the segments 113 and 114, but is adapted to engage one or the 30 other of said segments 113 and 114 upon movement of the disk about its axis. The arm 117 forms the common return of the solenoid circuits and is connected by conductor 120 through battery 121 to the respective windings of the solenoids 84 and 35 85. The contact disk 111 is normally held in a position to break both solenoid circuits by two opposed spiral springs 122 and 123 having bearing respectively against the 40 arms 124 and 125 which straddle suitable pins 126 upon the disk 111.

For pneumatically controlling a plurality of operative devices controlled by suitable pressure fluid motors, not shown, the port 45 30 of the main valve casing 24 is provided with a pipe 130 leading to one device, such for example as an engine control; the port 35 is provided with a pipe 131 leading to another device such for example as a 50 searchlight shutter; and the ports 40 and 41 provided respectively with pipes 132 and 133 connecting respectively to other pressure fluid controlled devices. Pressure fluid is admitted to the valve casing 24 by the 55 pipes 127 and 128 communicating respectively with the ports 26 and 27 and with compressed air tank 23 or like source.

For rotating the valve plug 25 to control the distribution of fluid to the various devices on the vessel, one end of the plug 25 is provided with a projecting shaft 134 coaxial therewith and rigidly secured thereto and upon this shaft 134 is fixedly secured a sleeve 135 having as a fixed part thereof a 60 ratchet wheel 136. At one side of the

ratchet wheel 136 there is a pinion 137 loosely mounted on the sleeve 135 and adapted to turn with respect thereto, this pinion 137 having a spring pressed pawl 138 arranged to coöperate with the ratchet 70 wheel 136 so as to turn the same in a clockwise direction when viewed as in Fig. 2. At the opposite side of the ratchet wheel 136 there is another pinion 140 also loosely mounted on the sleeve 135 and adapted to 75 turn with respect thereto and having a spring pressed pawl 141 arranged to coöperate with the ratchet wheel 136 so as to turn the same also in a clockwise direction when viewed as in Fig. 2. 80

For rotating the two pinions 137 and 140, two substantially parallel racks 142 and 143 are arranged to engage the opposite sides of the two pinions respectively, and these racks are rigid with a piston rod 144 which 85 is arranged to reciprocate in a fixed cylinder 145 and has fixed upon its inner end a piston 146 which is normally held in a predetermined position (as shown in Fig. 1) by a spiral spring 147 operatively located 90 in the cylinder 145. The end of the cylinder 145 opposite to the spring end is provided with a port 148 controlled by a slide valve 150 arranged to reciprocate in a casting 151 and alternately places the port 148 95 in communication with the supply pipe 152 and the exhaust pipe 153. The pipe 152 is connected to the air supply tank 23 and receives pressure fluid therefrom as required.

Any suitable means may be provided to 100 reciprocate the slide valve 150 but in the form of this invention shown the movable valve 150 is rigid with a core 154 which is drawn in one direction by the energizing of a solenoid 155 and in the other direction by 105 a spring 156, which latter also maintains the valve in normal position to cut off the supply of pressure fluid. The solenoid 155 is in a normally open circuit including the battery 157 and detector 158 which is in 110 the form of an evacuated glass bulb having a terminal 160, grid 161 and filament 162 heated by the local circuit of battery 163.

The grid 161 is connected as usual with the primary closed oscillatory circuit 164 115 having the variable condenser 165 and secondary transformer coil 166. The primary oscillatory circuit is tuned to the natural frequency of oscillation of an open aerial circuit comprising an antenna 170 in series 120 with a primary coil 171 and grounded at 172.

The construction and arrangement are such that when an impulse is received the solenoid 155 will be energized and thus pull the slide valve 150 to a position to close the 125 exhaust pipe 153 and admit pressure fluid to the cylinder 145 back of the piston 146 thereby overcoming the pressure of the spring 147 and forcing the piston 146 and the racks 142 and 143 to the right a sufficient 130

distance to rotate the pinion 137 in a clockwise direction through 45 degrees, while the pinion 140 is rotated in a counter-clockwise direction through 45°.

5 This action results in the pawl 138 engaging the ratchet wheel 136 and turning the shaft 134 through 45 degrees while the pawl 141 of the pinion 140 rides freely over the ratchet 136 without doing any work. At 10 the end of the impulse the solenoid 155 is de-energized and the spring 156 returns slide valve 150 to a position to cut off the pressure fluid to cylinder 145 and open the port 148 to the exhaust, whereupon the spring 147 15 causes the piston 146 to move to the left. The result of this is a reverse movement of the racks 142 and 143 whereupon the pinion 140 through its pawl operatively engages the ratchet wheel 136 and moves the shaft 20 134 in a clockwise direction through another 45 degrees. The return movement of the rack 142 rotates the pinion 137 in a counter-clockwise direction without affecting the ratchet wheel 136 since the pawl 138, in this 25 direction of movement, merely rides over the ratchet wheel 136.

In the operation of the form of the invention hereinbefore described, and shown in the several figures of the drawings, the movable body is normally steered automatically upon a predetermined course through the action of the gyroscope 96 and the cooperating mechanisms and for this purpose movable valve plug 25 is normally positioned 30 as shown in Fig. 3, though the same result may be obtained with this part in other positions as will later appear.

Assuming that the valve parts 24 and 25 are in the position shown in Fig. 3 for automatically controlling the course of the vessel, then the pipe 110 leading from the gyroscope clutch is open to exhaust through the port 38, passage 61, recess 45 and exhaust port 28, thus permitting the air to flow out 40 of the upper part of the cylinder 101 to allow the spring 107 to press the piston 103 upwardly and to clamp the yoke 105 against the cap 102, thus holding the spindle 99 and its disk 111 rigidly in fixed relation to the 45 gyroscope stem 97, and when the arm is thus held, if the vessel should deviate either to the right or to the left from its predetermined course, the arm 117 would make contact with one or the other of the contact 50 segments 113 and 114 according to the direction of movement. Assuming the deviation of the vessel to be to the right, then the contact arm 117 will swing with the vessel and contact with segment 114 whereupon the 55 circuit will be closed through conductor 116, right hand solenoid 85, conductor 120, battery 121 and arm 117, and the solenoid 85 energized to draw the valve 80 toward the right and permit compressed air to flow 60 from tank 23, pipe 90, annular passage 93,

70 pipe 92, passage 73 in plug 25, pipe 95 into the right hand end of cylinder 12 to move the piston 13 toward the left, thus swinging the rudder 10 clockwise to restore the vessel to its predetermined course. In this movement of the piston 13 toward the left, the left hand end of the cylinder 12 will be free to exhaust through the pipe 94, passage 75 70 in plug 25, pipe 91, to the valve casing 81 at the left hand end. When the piston 13 is moved a sufficient distance toward the left to cause the boat to turn to the left a sufficient amount to bring the arm 117 to rest again upon the insulation, the circuit through the right hand solenoid 85 will be 80 broken and the valve 80 will be restored to normal position by the springs 86 and 87, thus cutting off communication between the air supply pipe 90 and the pipe 92 and permitting this pipe 92 to exhaust through the 85 right hand end of the valve casing 81, thus relieving the right hand end of cylinder 12 and allowing the piston 13 to be returned to a central position by the springs 21 and 22. If the vessel should deviate toward the left, 90 the same automatic action takes place but bringing the solenoid 84 into operation and the set of pipes and ports necessary to admit air to the left hand end of cylinder 12 to shift the rudder to return the vessel to its 95 predetermined course.

When it is desired to take over the control of the vessel from the gyroscope and steer the vessel at will from a distance in response to impulses of radiant energy, the required 100 number of impulses are sent to turn the valve plug 25 to release the gyroscope control and position the plug passages to properly give the desired shifting of the steering piston 13.

Assuming that it is desired to steer the 105 vessel to the right by distant control and assuming that the valve parts 24 and 25 are in the normal position, as shown in Fig. 3, a relatively short impulse is sent and received by the antenna 170 whereby the solenoid 155 110 is energized to cause the valve 150 to admit pressure fluid to the cylinder 145 and the piston 146 reciprocated one stroke. The forward half of this piston stroke, by means of the rack 142, pinion 137, pawl 138 and 115 ratchet wheel 136, turns the valve plug 25 clockwise an eighth of a revolution to the position of Fig. 4, and upon the return stroke of the piston, which takes place in this instance immediately, the valve plug 25 120 is continued in its clockwise movement another eighth of a revolution by the action of the rack 143 and the associated parts. The transmitted impulse has thus brought the valve parts to the position shown in Fig. 5, 125 whereon the gyroscope control is released because the pipe 110 is now in communication by way of port 67 and recess 44 with the pressure fluid supply pipe 128 and consequently the piston 103 is moved against the 130

- pressure of the spring 107 to release the clutch heretofore connecting the parts together. Also the valve plug 25 is in position to connect the pipe 95 by passage 77 with the 5 exhaust port 34 and to simultaneously connect pipe 94 by passage 76 and recess 44 with the pressure fluid supply pipe 128. The pipes 91 and 92 from the electro-magnetic control valve are cut off and the steering 10 being accomplished independently of the automatic control. Pressure fluid is therefore admitted through pipe 94 to the left end of cylinder 12, thus forcing the piston 13 toward the right to swing the rudder 10 counter-clockwise to turn the vessel toward 15 the right. During this movement of the rudder the right hand end of cylinder 12 is free to exhaust through pipe 95, passage 77 and exhaust port 34.
- 20 When it is desired to steer the vessel toward the left the valve plug 25 is rotated through one half a revolution from the position shown in Fig. 5, by sending the required number of impulses to energize the 25 solenoid 155 the required number of times, whereupon the parts will be in the position indicated in Fig. 9 and the automatic control cut out as heretofore explained, and the right end of the cylinder 12 will be in communication 30 with the pressure fluid supply pipe 128 and the left hand end of the cylinder 12 will be open to the exhaust through the pipe 94, passage 77, passage 79' and exhaust port 34, and the rudder 10 will be rotated clockwise to steer the vessel toward the 35 left.
- When it is desired to operate any of the auxiliary devices under the control of the pipes 130, 131, 132 and 133 without disturbing 40 the automatic steering control the following operation takes place, it being assumed, by way of example, that the device controlled by pressure fluid through pipe 132 is the one to be actuated. With the 45 valve 25 in the neutral position of Fig. 3, a long impulse is transmitted to energize the solenoid 155 and cause pressure fluid to be admitted to the cylinder 145 to move the racks 142 and 143 to the right, as viewed in 50 Fig. 1, and hold them in such position for the length of the impulse. This rack movement turns the valve plug 25 through 45° into the position shown in Fig. 4 wherein air enters the pipe 127 and passes by way of 55 groove 43 and passage 57 to pipe 132 by which it is delivered to a suitable fluid operated means for operating the desired auxiliary device. The automatic steering control is not interfered with and remains operative 60 because the passages 72 and 75 have respectively moved into the position of the passages 73 and 70 so that the pipes 91 and 94, and 92 and 95 are still in communication. Also the pipe 110 is still in communication 65 with the exhaust port 28 so that the gyro-
- scope is effective. The impulse is of sufficient length to allow the pressure fluid to operate the selected device and when the impulse is stopped the return movement of the racks 142 and 143 turns the valve plug 25 70 through another 45° into the position shown in Fig. 5, which is a position to cut out the automatic steering control and to cause the boat to be steered to the right. Unless this is the action desired a short impulse is immediately sent to again reciprocate the racks 142 and 143 and cause the valve plug 25 to turn through 90°, namely from the position of Fig. 5 to the position of Fig. 7, which latter is a neutral position as far as the auxiliary 80 devices are concerned but allows the boat to remain under automatic control. In this manner the valve plug 25 may be rotated to any selected position by varying the length of the impulse, the long impulse being effective 85 to connect a desired auxiliary device with a source of pressure fluid for a sufficient time to operate that device and yet without disturbing conditions of automatic steering control. It should be noted that in 90 the present form it is preferable to have but one auxiliary device operable at a time, and consequently when the valve plug 25 is in a position to control one such device the pipes for the remaining auxiliary devices are 95 connected with the exhaust 33.
- In each of the positions indicated in Figs. 4, 6, and 8 and 10 the valve parts 24 and 25 are located to maintain the automatic steering control in operation while permitting the operation of an auxiliary device controlled by pressure fluid, and any desired position may be selectively obtained by sending the required number of impulses to shift the valve plug 25 through the portion 100 of a revolution to give the desired position. 105
- Having thus fully described my invention, what I claim is:
1. The combination with a plurality of independently operative fluid-actuated devices, of a source of pressure fluid, and means including a single rotatable valve member operative in response to an impulse of energy to cause the distribution of pressure fluid from said source to one of said devices to actuate the same and operative upon the cessation of said impulse to cause the distribution of pressure fluid from said source to another of said devices to operate the same. 110
2. The combination with a dirigible body, of steering means therefor, direction maintaining means carried by said body and automatically operative to control said steering means to direct said body upon a predetermined course, and means including a single rotatable valve member operative in response to an impulse of energy to move said valve to one position and operative as a result of the cessation of said impulse to 115
- 120
- 125
- 130

render said direction maintaining means inoperative and to change the direction of movement of said body through said steering means.

5 3. The combination with a dirigible body, of steering means therefor, direction maintaining means automatically operative to control said steering means to direct said body upon a predetermined course, a source 10 of pressure fluid, a multiple port valve including a single rotatable member normally positioned to admit pressure fluid to and render said direction maintaining means operative, means responsive to an impulse of 15 radiant energy to rotate said rotatable valve member to a position to cut off pressure fluid from said direction maintaining means and to admit pressure fluid to said steering means to direct said body in a predetermined manner, said responsive means being 20 operative upon the cessation of another impulse to rotate said rotatable member in the same direction to another position to restore said direction maintaining means as an automatic control of said steering means.

4. In a control system for dirigible bodies, a multiple port valve including a rotatable control element, a source of pressure fluid controlled by said valve, means for rotating 30 said control element in one direction, means responsive to impulses of radiant energy for operating said rotating means to move said control element to a predetermined position, means rendered operative upon the cessation 35 of an impulse to continue the rotation of said control element in the same direction to another position, a steering device, means controlled by said valve for causing said steering device to be automatically operated, and independent means controlled by 40 said valve for causing said steering device to be operated at will from a distance.

5. In a control system for dirigible bodies, a multiple port valve including a rotatable 45 control element, a source of pressure fluid controlled by said valve, means for rotating said control element in one direction, means responsive to impulses of radiant energy for operating said rotating means to move said control element to a predetermined position, means rendered operative upon the cessation 50 of an impulse to continue the rotation of said control element in the same direction to another position, a steering device, means controlled by said valve for causing said steering device to be automatically operated, independent means controlled by said valve for causing said steering device to be operated at will from a distance, and means 55 for rendering said automatic means inoperative when said steering device is controlled at will.

6. In a control system for dirigible bodies, a steering means, a multiple port valve including a rotatable control element, a source

of pressure fluid controlled by said valve, a plurality of distributing pipes connected respectively to auxiliary control devices, and means responsive to impulses of radiant energy to rotate said valve to selectively control said distributing pipes and to simultaneously maintain automatic control of said steering means.

7. In a control system for dirigible bodies, a steering means, a multiple port valve, a source of pressure fluid controlled by said valve, a plurality of distributing pipes connected respectively to auxiliary control devices, and means responsive to impulses of radiant energy to shift said valve to selectively control said distributing pipes and to simultaneously maintain automatic control of said steering means.

8. In a control system for dirigible bodies, a steering means, a multiple port valve, a source of pressure fluid controlled by said valve, a plurality of distributing pipes connected respectively to auxiliary control devices, and means responsive to a relatively long impulse of radiant energy to shift said valve to admit pressure fluid to one distributing pipe and to simultaneously maintain automatic control of said steering means and responsive to a succeeding short impulse to restore said valve to a neutral position with said steering means under automatic control.

9. In a control system for dirigible bodies, a steering means, a multiple port valve including a single rotatable valve member, a source of pressure fluid controlled by said valve, a plurality of distributing pipes connected respectively to auxiliary control devices, and means responsive to a relatively long impulse of radiant energy to rotate said valve member to admit pressure fluid to one distributing pipe and to simultaneously maintain automatic control of said steering means and responsive to a succeeding short impulse to restore said valve to a neutral position with said steering means under said automatic control.

10. The combination with a dirigible body, of steering means therefor, direction maintaining means carried by said body and automatically operative to control said steering means to direct said body upon a predetermined course, a source of pressure fluid, a single rotatable valve member operative to control the admission of said pressure fluid to said steering means, a plurality of distributing pipes connected respectively to auxiliary devices and controlled by said valve, and means responsive to impulses of radiant energy to position said valve to select a predetermined distributing pipe for pressure fluid and to simultaneously maintain said automatic direction maintaining means operative to steer said body.

11. The combination with a plurality of

independently operative fluid-actuated devices, of a source of pressure fluid, and means including a valve member operative in response to an impulse of energy to cause 5 the distribution of pressure fluid from said source to one of said devices to actuate the same, and operative upon the cessation of

said impulse to cause the distribution of pressure fluid from said source to another of said devices to operate the same.

Signed at New York, in the county of New York and State of New York, this 27th day of May, A. D. 1918.

ALBERT D. TRENOR
